PAGE 2

Fig. 3

Fig. 5

FIG. 1 is a top view of a collapsible seat and gun rest combination embodying my new design;

FIG. 2 is a side view;

FIG. 3 is a front view;

FIG. 4 is a view of the article in its collapsed form; and

FIG. 5 is an elevational view of the article in its collapsed form and taken from the left of FIG. 4.

I claim:

The ornamental design for a collapsible seat and gun rest combination as shown.
